UNITED STATES PATENT OFFICE.

JOHN ELSTON RHODES, OF TEANECK, NEW JERSEY.

TELEPHONE ATTACHMENT.

1,370,152.

Specification of Letters Patent.

Patented Mar. 1, 1921.

Application filed May 6, 1920. Serial No. 379,280.

To all whom it may concern:

Be it known that I, JOHN ELSTON RHODES, a citizen of the United States, and a resident of Teaneck, county of Bergen, and 5 State of New Jersey, have invented certain new and useful Improvements in Telephone Attachments, of which the following is a specification.

This invention relates to telephone attachments, and broadly considered, comprehends the provision of a novel and simply constructed device for attachment to the mouth piece of a telephone transmitter which is so constructed as to provide an effective guard 10 for preventing the lips of the speaker from coming into contact with the rim of the mouth piece cone. Thus the attachment minimizes the possibility of the contraction of contagious diseases by telephone users. 15 One of the important objects of the present invention is to provide an attachment for the above purpose which can be easily and quickly applied to or removed from the telephone transmitter, and may also be 20 readily displaced or moved to an inoperative position upon the mouth-piece. 25

It is another object of my invention to provide an attachment which is of such construction as to afford means for the display 30 of advertising matter, conspicuously located so that it will be in the direct line of vision of the telephone user.

With the above and other objects in view, my invention consists in the provision of an 35 attachment for telephones as above characterized, and in the form, construction and relative arrangement of its several parts as will be hereinafter more fully described, illustrated in the accompanying drawings, 40 and subsequently incorporated in the subjoined claims.

In the drawings, wherein I have illustrated several practical and satisfactory embodiments of the invention, and in which 45 similar reference characters designate corresponding parts throughout the several views:

Figure 1 is a side elevation of a telephone transmitter having the attachment applied thereto, and also showing the latter in dotted lines, in an inoperative position.

Fig. 2 is a front elevation.

Fig. 3 is a top plan view.

Fig. 4 is a perspective view of the attachment removed from the transmitter, and,

Fig. 5 is a front elevation, the mouth

piece cone being in section, and illustrating a slightly modified form of the device.

Referring in detail to the drawings, and more particularly to Figs. 1 to 4 thereof, 5 designates the mouth-piece cone of a telephone transmitter, to which the present attachment is adapted to be applied. The attachment proper is formed from a single length of resilient wire bent to provide the 10 convergently disposed intermediate portions 6. From the free ends of these convergent portions 6 of the wire, the ends of the wire are laterally extended and oppositely bowed, as at 7, to provide downwardly projecting 15 clamping arms which are adapted to embrace the mouth-piece cone 5. These clamping arms terminate in the eyes 8, which eliminate rough or ragged edges such as would result from the cutting of the wire. 20

At the other or more widely spaced ends of the side portions 6, the wire is abruptly bent or curved upwardly, as at 9, and these bent portions of the wire are adapted to exert a resilient frictional bearing engagement 25 upon the perimeter of the mouth piece cone, so that they will tightly hug the latter. The central portion of the wire, constituting the connection between the side portions 6, projects in advance of the mouth-piece cone for 30 about one quarter of an inch, and is upwardly bowed or curved, as at 10, such curved central portion of the wire being disposed substantially in concentric relation to the periphery of the transmitter mouth 35 piece.

It will be seen that the attachment as thus far described, consists merely of a single resilient length of wire, having the bowed clamping arm 7 to snugly embrace the 40 mouth-piece cone 5 at the base thereof, and the central forwardly projecting guard portion 10, which serves to prevent contact of the lips of the speaker against the rim or perimeter of the mouth piece.

In order to increase the durability and utility of the attachment I propose to provide a connecting bridge plate 12 between the converging side portions 6 of the wire attachment. This bridge plate is curved in 45 concentric relation to the mouth piece, and has its side edges turned around the portions 6 of the wire, as at 13. Thus it will be appreciated that this connecting or bridge plate greatly reinforces and strengthens the 50 structure of the wire attachment. The plate 12 also is held in close relation to the pe-

riphery of the transmitter mouth-piece by the side portions 6 of the wire. This plate may consist of celluloid, cardboard, tin or other sheet material, and upon the convex 5 surface thereof, suitable advertising matter may be printed or otherwise delineated.

As heretofore observed, when the attachment is applied, the bends 9 in the wire exert a frictional pressure upon the rim or 10 perimeter of the mouth-piece, and thus serve to yieldingly retain the attachment in its operative position, as seen in full lines in Fig. 1. However, when it is desired to dispense with the use of the attachment, it 15 may be readily swung or shifted upon the transmitter mouth-piece to the lower side thereof, as shown in dotted lines in Fig. 1, without necessitating its removal.

In Fig. 5 of the drawings, I have disclosed 20 a slightly modified embodiment of my invention, wherein the bridge plate 12 at its rear or narrower end is formed with an angularly bent upwardly projecting portion 14, provided with side wings or extensions 15 projecting in opposite directions from the bridge plate, and in concentric relation to the periphery of the transmitter box. The portion 14 of the bridge plate is provided with an opening 16 therein, through which 30 the call number of the telephone is visible.

In all other respects the attachment is of 35 the same construction as previously described. In either construction the attachment may be readily rotated upon the transmitter mouth-piece to its lower inoperative position, so that one may use the telephone, if desired, without having the lips come into contact with the guard portion 10 of the attachment. The side wings 15 of the modified 40 construction provide additional advertising space, which may be effectively utilized as seen in Fig. 5. Due to the location of the attachment upon the transmitter mouthpiece and the arrangement of the advertising matter thereon, the latter will be, at all times, in the direct line of vision during 45 the use of the telephone.

From the foregoing description considered in connection with the accompanying drawings, the construction, manner of operation and several advantages of my improved telephone attachment will be readily understood. Owing to the extreme simplicity of the device, it is obvious that the same may 55 be manufactured at a very low cost, and that its serviceability and utility is materially increased by the fact that the attachment readily lends itself to the effective display of advertisements.

60 In the foregoing description I have particularly described several constructions of the device which are of a practical and satisfactory character, but it will, nevertheless, be understood that the attachment is also susceptible of numerous other alternative con-

structions, and I accordingly reserve the privilege of adopting such additional modifications in the form, proportion, and relative arrangement of the several parts as may be fairly embodied within the spirit and 70 scope of the invention as claimed.

I claim:

1. An attachment for telephone transmitters comprising a single length of resilient wire having end portions for detachable 75 clamping engagement upon the smaller end of the mouth-piece cone in contact with the transmitter body, side portions extending longitudinally over the mouth-piece cone, and an intermediate portion connecting the side 80 portions of the wire disposed forwardly of the perimeter of the mouth-piece cone in the operative position of the attachment and constituting a guard to prevent contact of the lips of the speaker with the mouth-piece, 85 and means connecting the side portions of the wire to each other to prevent the spreading movement thereof.

2. An attachment for telephone transmitters and the like, comprising a single length 90 of resilient wire, having end portions bowed in opposite directions to clampingly embrace the mouth-piece cone at the small end thereof, and side portions projecting forwardly from the end portions, and exerting 95 a frictional retaining pressure at their forward ends upon the perimeter of the mouth-piece cone to prevent casual circumferential movement of the attachment, said side portions of the wire being connected by a central upwardly bowed portion constituting a 100 guard projecting in advance of the mouth-piece to prevent the lips of the speaker contacting with the mouth-piece cone, and a bridge plate connecting the spaced side portions of the wire to prevent spreading movement thereof.

3. An attachment for telephone transmitters and the like comprising a single length 110 of resilient wire having oppositely bowed end portions to embrace the mouth-piece cone, and side portions projecting forwardly 115 from said end portions and connected by a central portion of the wire constituting a guard to prevent the lips of the speaker contacting with the mouth-piece cone, and means connecting said side portions of the wire to hold the same against relative spreading movement.

4. An attachment for telephone transmitters and the like comprising a single length 120 of resilient wire having oppositely bowed end portions to embrace the mouth-piece cone, and side portions projecting forwardly 125 from said end portions and connected by a central upwardly bowed portion of the wire constituting a guard to prevent the lips of the speaker contacting with the mouth-piece cone, and a bridge plate connecting said side portions of the wire, and disposed in con- 130

centric relation to the mouth-piece cone, said bridge plate adapted to bear advertising matter on its surface.

5. An attachment for telephones comprising a resilient wire having connected side portions and oppositely bowed clamping portions for detachable engagement with a part of the telephone structure, a bridge plate connecting said side portions, and pro-

vided at one end with an extension, said 10 bridge plate and the extension being adapted to bear advertising matter, and the extension being provided with an opening through which the call number of the telephone is visible.

In testimony that I claim the foregoing as my invention, I have signed my name.

JOHN ELSTON RHODES.
